UNITED STATES PATENT OFFICE.

FRANK JOS. WEBER, OF FOND DU LAC, WISCONSIN.

ILLUMINABLE ADVERTISING DEVICE.

1,075,177.

Specification of Letters Patent.

Patented Oct. 7, 1913.

Application filed March 23, 1912. Serial No. 685,872.

To all whom it may concern:

Be it known that I, FRANK JOSEPH WEBER, a citizen of the United States, and a resident of Fond du Lac, State of Wisconsin, have 5 invented a new and useful Improvement in Illuminable Advertising Devices, of which the following is a specification.

This invention has for its object the providing of an automatic device which will 10 display in rotation a series of advertisements, displaying each advertisement for a definite period of time; also to provide means whereby the advertisement is illuminated at night time during the interval that 15 it is displayed, and to so arrange the illuminating means as to automatically interrupt the illumination during the interval that the machine is operated to change from one advertisement to another.

20 My invention further has for its object to provide simple and inexpensive mechanism for the purpose mentioned, and to this end my invention embodies the special features and combination of parts hereinafter more 25 fully set forth, and illustrated in the accompanying drawings constituting a part of this specification.

In the drawings: Figure 1 is a side elevation of my machine showing, however, only the frame work and the mechanism therein 30 provided; the casing being omitted, since that can be supplied as desired by the builder; Fig. 2 is a diagrammatic front elevation of my machine illustrating that I 35 provide frame-like means for standing out the advertisement displayed; Fig. 3 is a transverse section taken approximately on line A—A of Fig. 1, showing part of the mechanism for intermittently driving the 40 endless apron bearing the advertisements; Fig. 4 is a transverse section approximately taken on line B—B of Fig. 1, showing another part of the motion transmitting device, showing also in dotted lines the parts 45 shown in Fig. 3, so as to fix their relative positions; Fig. 5 is a perspective of the spring-controlled locking pin by which the mechanism running the endless band is 50 intermittently connected with the driven pulley, said pin serving to make the electric circuit for the electric lamp illuminating the advertisements at night time; Fig. 6 is a side elevation showing a portion of the frame and a semi-circular cam ring thereon 55 affixed, serving both to lift the locking pin out of its locking position and to establish

the electric circuit for intermittent intervals during the running of my device; this figure also diagrammatically illustrates the electric wiring, and the connection of the lamp with 60 such wiring; Fig. 7 is a longitudinal sectional view on a line x—x of Fig. 3, looking toward the right, and shows an inner face elevation of the driven pulley of my device, the electric contact plate thereto affixed, and 65 the relative position of the semi-circular cam ring shown in Fig. 6; and Fig. 8 is a diagrammatic view of the electric wiring of my machine, controlling its illumination by the electric lamp; and Fig. 9 illustrates a modified type of bearing for the rollers, on which 70 travels the endless band of my device.

My device comprises a suitable frame, a, mounted on legs vertically adjustable and preferably supported on casters b. The 75 frame has journaled in its top and bottom horizontal members a', a' a series of transversely arranged rollers d, on which travels an endless band e, carrying the advertisements. The band e may be adapted to have 80 changeable advertisements written thereon in chalk, or otherwise, or the advertisements may be permanently imprinted on the band as convenient. The roller d' serves as a 85 tightener and is journaled in an adjustable bracket 3 vertically movable by operating the screw z, in order to tighten the band e as required. The latter has a series of perforations at its sides which register with the teeth f on the extremity of the rollers d. 90

A V-faced driven pulley g is rigidly mounted on the stub-shaft h, bearing at one end in a frame member a' and at the other end in a supplemental frame-member a'', as shown in Fig. 3. On the driven pulley g 95 is fastened an electric contact-plate i, to which is affixed a laterally projected, hinged pin, controlled by a spring j, in the manner hereinafter more fully described. On the stub-shaft h is also rotatably mounted the hub m of a circular disk n. The latter is provided in its periphery with two semi-circular grooves or recesses p, p', diametrically opposite each other and of a size to accommodate the pin k. There is also 105 rigidly mounted on the hub, m, a gear o. A semi-circular cam ring q is rigidly fastened to the frame a, being located as more clearly shown in Figs. 6 and 7. The cam ring q is arranged concentric with the disk n, but 110 its diameter is slightly greater than the diameter of the latter, as shown at n'. The

pin *k* provides the means for intermittently connecting the disk *n* with the driven pulley *g* for a part of the latter's revolution, thus progressively moving the band *e* and 5 permitting it to be at rest for an interval. The pin *k* will ride on the periphery of the cam ring *q* during one half the revolution of the pulley *g*. The ends of the cam ring are inclined or curved so as to facilitate the 10 passing of the pin *k* into and out of the grooves *p*, *p'* and from and onto the periphery of the cam ring *q*. A pinion *r* is rigidly attached on the driven roller *d*², said pinion meshing with the gear *o*, the 15 remaining rollers receiving motion from the band running over them.

s represents a prime mover in the form of an electric motor. The source of electric energy may be supplied as convenient, 20 though shown in Fig. 2 as consisting of a battery *t*. *u* is an electric lamp electrically connected with said source of electricity. The lamp *u* is placed behind the frame part *y*, rearward of the band *e*, which travels back 25 of said frame part *y*, the band being made of transparent material so as to lie illuminable by the lamp, as shown in Fig. 1. The frame part *y*, at the front of my machine, serves as a frame to set out the advertisement 30 exhibited for the time.

The wiring system (see Fig. 8) is as follows: 1 and 2 are the main wires of the series circuit. In this circuit is a switch *w* and a light *u*. The wire 4 electrically connects the light *u*, and its other end bears 35 constantly against the contact plate *i*, the latter carrying the current to the pin *k*. The wire 2 is connected with the cam ring *q*, so that the circuit is completed when the 40 pin *k* and cam ring *q* contact, thereby energizing the light *u*.

The action of my device is as follows: The motor *s* runs constantly and is connected by a belt *s'* with the driving pulley 45 *g*. Supposing the lock pin *k*, carried by the latter, to be engaged with the groove *p* of the disk *n*, the latter will travel with the driven pulley *g* for one half of its revolution. The pin *k* is now brought into contact with one end of the cam ring *q*, and in 50 striking the inclined portion *q'* is lifted out of the groove *p* of the disk *n*, and the latter then remains at rest, while the pin *k* travels over the semi-circular cam ring *q*. While 55 the disk *n* remains at rest, as mentioned, one of the advertisements is being exhibited. If the exhibition take place in the night time, and the switch *w* of the lamp circuit is closed, the pin *k*, while riding on the cam 60 ring *q*, closes the lamp circuit and causes the advertisement to be illuminated. When the pin *k* has traveled to the opposite end of the cam ring *q*, it will slide into the groove *p*, being forced into such groove by the action 65 of the spring *j*. The disk *n* is thus con-

nected with the pulley *g*, and the band-moving mechanism is operated for another half revolution of the pulley *g*, thereby causing the displayed advertisement to be moved out of display position and another advertisement to be moved in its place. As soon as such other half revolution has been completed, the pin *k* is again forced out of contact with the disk *n*, allowing the latter to remain at rest, and so on, the operation repeats itself. It will also have been noted that when the pin *k* passes from the cam ring *q*, the lamp circuit is interrupted so that during the interval that the band *e* is moved to change the advertisement displayed, the lamp *u* will be extinguished. This result is especially effective for night time advertising.

A modified type of roller bearing for the roller *d* is shown in Fig. 9. The hollow or tubular roller *d*³ is journaled on a shaft rod *d*⁴, the latter serving also as a brace rod to the frame. Within the roller *d*³ are provided bearing sleeves, as 5, 6, the latter bearing on the shaft rod *d*⁴. *f'* represents the peripheral pins for engaging the curtain. Washers or collars, as 7, are inserted between the end of the roller and the frame members *a'*.

In order to cause my device to attract 95 attention, the endless band *e* may have a series of interchangeable parts of a pictorial advertisement and the frame have a nonchangeable part of the picture, as illustrated in Fig. 2.

I claim:

1. In an illuminable advertising device comprising a series of rollers and an endless band traveling on said rollers, the combination of a driven rotating member; a coupler carried by said driven member; a disk revolvably mounted on an axis coincident to that of the driven member, said disk provided with means on its periphery, located equi-distant from each other, for engagement by said coupler; means for transmitting motion to one of said band rollers, such means operated by said disk; means whereby said coupler is periodically disengaged for an interval from said disk; and an electric lamp for illuminating the band, the poles of the circuit of which lamp are connected with said coupler and the coupler disengaging means, whereby the lamp is energized while said disk is at rest and extinguished while said disk is rotating.

2. In an illuminable advertising device comprising a series of rollers and an endless band traveling on said rollers, the combination of a driven rotating member; a spring-controlled yielding pin carried by said driven member; a disk revolvably mounted on an axis coincident to that of the driven member having grooves in its periphery, located equi-distant from each other, for

- engagement by said pin; means for transmitting motion to one of said band rollers, such means operated by said disk; means whereby said pin is periodically disengaged 5 for an interval from said disk; and an electric lamp for illuminating the band, the poles of the circuit of which lamp are connected with said pin and with said disengaging means, whereby the lamp is energized 10 while said disk is at rest and extinguished while said disk is rotating.
3. In an illuminable advertising device comprising a series of rollers and an endless band traveling on said rollers, the combination 15 of a driven rotating member; a spring-controlled yielding pin carried by said driven member; a disk revolvably mounted on an axis coincident to that of the driven member having grooves in its periphery, located equi-distant from each other, for engagement by said pin; means for transmitting motion to one of said band rollers, such means operated by said disk; a cam arranged concentric with said disk, whereby 20 said pin is disengaged from said disk, periodically, for an interval; and an electric lamp for illuminating the band, the poles of the circuit of which lamp are connected with 25
- 5 said pin and with said cam, whereby the lamp is energized while said disk is at rest and extinguished while said disk is rotating.
4. In an illuminable advertising device comprising a series of rollers and an endless band traveling on said rollers, the combination 30 of a driven rotating member; a coupler carried by said driven member; a disk revolvably mounted on an axis coincident to that of the driven member, said disk provided with means on its periphery, located equi-distant from each other, for engagement by said coupler; means for transmitting motion to one of said band rollers, such means operated by said disk; means whereby said coupler is periodically disengaged 35 for an interval from said disk; and an electric lamp for illuminating the band, the poles of the circuit of which lamp are connected with said coupler and with said fixed cam, whereby the lamp is energized while 40 said disk is at rest and extinguished while 45 said disk is rotating.
